UNITED STATES PATENT OFFICE.

EDWARD FARRINGTON CHANDLER, OF BROOKLYN, NEW YORK.

MACHINE FOR HOLDING, DISPLAYING, AND INDORSING CHECKS.

1,032,378.

Specification of Letters Patent.

Patented July 16, 1912.

Application filed July 9, 1908. Serial No. 442,710.

To all whom it may concern:

Be it known that I, EDWARD F. CHANDLER, a citizen of the United States, residing in Brooklyn, in the county of Kings and State of New York, have invented a new and useful Improvement in Machines for Holding, Displaying, and Indorsing Checks, of which the following is a specification.

10 This invention relates to an improved construction of machine for holding, indorsing or stamping and displaying checks and more particularly to certain improvements upon the machine for holding, 15 stamping and displaying checks shown, described and claimed in the application for Letters Patent filed by me November 23, 1905, Serial Number 288,765.

This invention is intended for use in 20 banks, counting houses and the like, the purpose of the invention being to provide a machine in which a number of checks can be placed, the machine being arranged adjacent an adding machine and one face 25 thereof in plain view, so that the face of the check may be displayed for a definite length of time to the operator of the adding machine so that the amount of the check can be quickly and easily read and the 30 adding machine operated during the interval of time which elapses between the displaying of one check and the feeding, indorsing and displaying of the next check.

Another object of the present improvement is to provide a machine in which the feeding, indorsing and displaying of the check will be carried on at a uniform rate of speed, irrespective of the width of the check as it is a well known fact that there is no 35 uniformity in the width of checks and consequently some provision must be made for compensating for the differences between narrow and broad checks, as it is essential that each check should be displayed a definite 40 length of time irrespective of its width.

Another object of the present construction is to provide a machine in which all of the operations will be thoroughly automatic after the electric switch has been 45 shifted for the purpose of placing the machine in motion. This enables the person operating the adding machine to arrange a number of checks in the hopper of the machine, throw the switch and proceed with 50 the operation of the adding machine as each check will be fed from the hopper,

indorsed with the bank stamp upon the back thereof and after being so stamped or indorsed the face thereof will be displayed to the operator for a sufficient length of 60 time to enable him to clearly read the amount of the check and transcribe the same by means of the machine.

With these objects in view and also certain other objects as will appear hereinafter, as the invention is more full described, the invention consists in the various novelties of construction, combination and arrangement all of which will be fully described hereinafter and pointed out in 70 the claims.

In the drawings forming a part of this specification—Figure 1 is a vertical sectional view of the machine. Fig. 2 is a longitudinal sectional elevation. Fig. 3 is 75 a sectional plan on the line 3—3 of Fig. 1. Fig. 4 is a sectional plan on the line 4—4 of Fig. 1. Fig. 5 is a detail view of the indorsing or stamping roll and associated parts. Figs. 6 and 7 are detail sectional views on 80 the line 6—6 of Fig. 5, Fig. 6 showing the circuit as broken and Fig. 7 showing the circuit closed. Figs. 8, 9, and 10 are detail sectional views on the line 8—8 of Fig. 5, Fig. 8 showing the parts in the same position as they are in Fig. 6, Fig. 9 showing the parts in the same position they are in Fig. 7, and Fig. 10 shows the position the parts assume in case the check is of unusual 85 length. Fig. 11 is a detail perspective view 90 of the hopper. Fig. 12 is a detail perspective view of the follower. Fig. 13 is a detail view partly in section showing the mechanism for throwing the machine into and out of operation. Fig. 14 is a detail 95 perspective view of the movable hanger in which is arranged the upper end of the vertical driving shaft. Fig. 15 is a detail view illustrating the connection between the motor shaft, vertically driven shaft and the 100 brake mechanism. Fig. 16 is a detail perspective view of the movable armature and bar connected therewith. Fig. 17 is a diagrammatic view illustrating the electric 105 circuits and connected parts employed in connection with the machine. Fig. 18 is a detail view illustrating the manner of supporting the segregating disks.

The general appearance of the machine is very much the same as the one shown in 110 the application previously referred to and in the practical embodiment of my present

construction I employ a case A comprising a bottom A', front A², back A³ and ends A⁴, the upper end of the casing being constructed with a hopper A⁵ into which the 5 checks are placed on edge or in vertical position as most clearly shown in Fig. 1 and for the purpose of maintaining these checks in a proper position, I employ detachable guides A⁶, the hooked ends A⁷ of which 10 engage the upper rear edge of the hopper while the lower ends A⁸ bear upon the face of the hopper adjacent the openings A⁹, in which the feed rolls hereinafter described, turn for the purpose of feeding the checks. 15 The front of the casing is formed with an opening A¹⁰, in which is arranged a glass panel A¹¹, and behind which the checks are held for the purpose of displaying them for a definite length of time as will be fully explained hereinafter. 20

The back of the case is constructed with a hinged door A¹² so that access to the interior of the machine can be conveniently had whenever desired. As before stated the 25 checks are arranged in the hopper on edge, that is, resting on their bottom longitudinal edge and are held in substantially a vertical position against the detachable guides by means of a movable follower, B, provided with rollers B', at each end, and a roller B² at the center of the bottom edge of the hopper, which travel upon the inclined bottom of the hopper, the front face B³ of the follower contacting with the bunch 30 of checks and holding them in their proper upright position, said follower resting normally against the bunch of checks by gravity inasmuch as the said follower travels upon the inclined bottom of the hopper. 35

40 Resting upon the bottom of the hopper and beneath the follower are the metal strips C, the inner ends of which project beyond the inner end of the bottom of the hopper and are curved downwardly into the throat 45 of the hopper as most clearly shown in Fig. 1, and this curved end C' is slotted as shown at C² and mounted in each slot is a segregating disk being held in clips C⁴ rigidly connected to a longitudinal bar C⁵ arranged 50 beneath the bottom of the hopper and carrying tubular castings C⁶ through which a bolt C⁷ passes, the threaded end of said bolt being screwed into the wall A' which is arranged in the casing and constitutes the 55 front side of the passageway through which the check is fed.

The opposing wall A¹² is a continuation of the back of the hopper as most clearly shown in Fig. 1. The bolts C⁷ extend a considerable distance through the tubular castings C⁶ and springs C⁸ bearing upon said castings and the nut C⁹ serves to force the segregating disks the proper distance toward the feed rolls D which will be fully described 65 hereinafter, and the movement of the tubu-

lar castings and consequently the segregating disks are limited by means of set screws C¹⁰ which pass through the depending end of the castings C⁶ and bear against the wall A¹¹ as most clearly shown in Fig. 1. 70

The strips C are yieldingly projected inwardly by means of springs C¹¹ each spring being fastened at the inner end to a short pin C¹² depending from the bottom of the hopper while the other end of each spring is connected to a screw C¹³ carried by the plate C and which works in a slot C¹⁴ produced in the bottom of the hopper. This construction enables the metal strips to be held in proper position with reference to 80 the segregating disks, and consequently in proper position with reference to the checks which are being fed from the hopper to the stamping mechanism hereinafter fully described. 85

There are preferably two segregating disks and it will be noted that the bottom of the hopper is cut away as shown in Fig. 11, and the back of the hopper is also cut away at a point directly opposite as shown at A⁹, and working therein are the feed rolls D, which may be of any suitable material, but preferably of rubber or at least rubber faced, in order to insure a firm grip upon the check. These feed rolls are so arranged with reference to the segregating disks that the checks will rest with their edges upon said rolls and disks and when the rolls are operated the checks will be fed one at a time down into the passageway formed by the walls 90 A¹¹ and A¹². The rolls D are mounted upon a horizontal shaft D' journaled in the casing and adjacent one end of the shaft D' has a worm-gear D² mounted thereon, which gear is adapted to mesh with the worm D³ 95 carried upon the upper end of the vertical driving shaft D⁴, said worm D³ being arranged within a swinging hanger D⁵, the side members of said hanger being pivoted upon the shaft D', and these side members 100 are connected by means of the top and bottom bearing plates D^{6a} between which the worm D³ is arranged. The purpose of this swinging hanger is to keep the worm D³ and worm gear D² always in mesh, and yet permit the vertical driving shaft D⁴ to have a limited swinging movement at its lower end, said lower end being journaled in a movable bar E which carries an armature E' at one end which armature is adapted to 110 be attracted by the electro-magnet E² whenever said magnet is energized and when said armature is attracted the shaft D⁴ is caused to move so as to bring the worm gear D⁶ into mesh with the worm D⁷ which is 115 mounted upon the shaft of the motor, and at the same time the brake F which is fastened at one end F' to the side of the casing and at the other end to a post F² arranged upon the end of the bar E said band en-

120 125 130

5 circling a brake disk F³ arranged upon the end of the motor shaft which also carries the worm D⁷. The spring E³ throws the armature away from the electro-magnet the moment the current is broken and consequently the bar E is shifted so as to move the vertical driving shaft out of engagement with the motor and the brake is applied so that the motor is stopped. It will

10 therefore be understood that checks are arranged upon edge in the hopper and the motor started and this motion is communicated through the gearing devices to the feeding rolls which co-acting with the segregating disks serve to feed the checks one at a time down into the passageway formed between the walls A¹¹ and A¹².

15 The circuits controlling the electric motor will be fully described hereinafter, and I will now proceed to describe the manner of indorsing and stamping each check upon the back thereof, as it is fed from the hopper to the display portion of the casing.

20 The shaft D' has a gear wheel G mounted upon the outer end thereof, which gear meshes with a similar gear G', which is mounted upon the outer end of a shaft G², which is mounted in the casing below the bottom of the hopper and mounted upon this 25 shaft G² is a cylindrical platen G³ which is adapted to co-act with the stamp or indorsing roll H, which carries the bank stamp H', which is to be impressed upon the back face of the check as it is passed down through 30 the passage-way and it will be noted that the walls A¹¹ and A¹² are cut away to permit the faces of the platen and stamping roll to contact with each other as most clearly shown in Figs. 5, 6 and 7.

35 The stamping roll H is mounted loosely upon a shaft H² which is adjustably mounted upon the rods H³ screwed into the walls A¹² and springs H⁴ serve to hold the shaft H² so that the stamping rolls will contact 40 with the platen and set screws H⁵ are passed through the ends of the shaft for the purpose of regulating the exact position the shaft shall occupy with reference to the walls A¹².

45 The stamping roll is cut away as shown at H⁶ so that the check will have ample room to pass downwardly between the platen and stamping roll prior to the stamping operation and mounted upon the stationary

50 shaft adjacent one end of the stamping roll is a finger I, said finger being of such length as to project across a passage which the check traverses and this finger is normally held in a horizontal position by means of

55 the pin I', projecting from the end of the stamping roll and a spring I² is connected to a stud I³ carried by the finger, the opposite end of said spring being connected to the end of the stamping roll as shown at I⁴ for 60 the purpose of normally maintaining the

finger I, upon the pin I'. At the opposite end of the stamping roll is a disk K having an insulated portion K', said disk being of any suitable conductive material, and a contact plate K², contacts with the disk and a contact plate K³ is adapted to engage the insulated portion K', when the finger I is in a horizontal position as most clearly shown in Fig. 8.

65 Conductor wires lead from the contact plates K² and K³ to the magnets and electric motor as hereinafter fully described. As the check is fed from the passage, it engages the finger I, with sufficient force to turn the roll a sufficient distance to move the disk K, so that the insulated portion K', is moved from beneath the contact plate K³, and the circuit will then be closed, and the circuit being closed, the moving parts of the machine will be set in motion and the checks 70 will be fed from the hopper down between the plate and stamping roll and the stamping roll and platen being once brought into contact with each other as shown in Fig. 9, the check will be held between them and stamped or indorsed. These movements will 75 continue until the disk K is turned so as to bring the insulated portion K', beneath the contact plate K³ when the circuit will be broken and the movements of the machine stopped and this will occur just after the check has passed beyond the stamping roll.

80 In case the check is of extraordinary width I provide against the premature breaking of the circuit by providing for a limited movement of the finger I, as most clearly shown in Fig. 10, as it will be noted that as the stamping roll turns, the end of the finger will come into contact with the check 85 and the roll will be stopped, the finger being pressed downward until it will be stopped, the finger being pressed downward until it contacts with the stop finger I⁵ projecting from the end of the roll and by having this free movement of the finger, the motion of the insulated disk is retarded until the check has passed completely through the stamping mechanism, and the spring I² will 90 then act upon this finger to bring it back to 95 its normal position and in the meantime the disk K will have been brought around to such position as to open the circuit.

100 The wall A¹² is continued downwardly substantially parallel with the glass panel A¹⁴ as most clearly shown at A¹⁵ and is then diverted in a rearwardly direction as shown at A¹⁶ in order to provide suitable guideways for a drawer A¹⁷ into which the checks are dropped after they have been displayed 105 for the desired length of time. Upon the rear of the wall or partition A¹⁵ is journaled a rock shaft L, carrying depending arms L', having hooked lower ends L² which 110 project forwardly through the openings L³ 115

and which hooked ends serve to catch the check after it has been passed through the stamping mechanism and holds said check directly opposite the glass panel A¹⁴ and 5 in such position that it can be clearly seen by the operator of the adding machine. The amount of the check is then transcribed by means of the adding machine, and the operator is then ready to drop said check and 10 start the mechanism feeding the next succeeding check and this he accomplished by pressing a button, for the purpose of energizing a magnet M, arranged centrally of the case and so positioned as to attract the 15 armature M', which is arranged upon the central depending arm L', and when this armature is attracted, all three of the arms are moved so as to withdraw the hooked ends L² from beneath the bottom of the check and 20 the check then dropped into the drawer A¹⁷.

It will be understood that as soon as the check passes the stamping mechanism the current to the motor is cut off and the moving parts of the machine are thereby 25 stopped and the check is therefore permitted to remain upon the hooked ends L² until the operator pushed the button for the purpose of energizing the magnet, and in so doing the motor is restarted and consequently the 30 next succeeding check is started on its journey from the hopper to the stamping mechanism.

The dash pot N is connected to one of the arms L' for the purpose of rendering the 35 movements of the said arms easy and noiseless.

In Fig. 17 I have shown a diagrammatic view for the purpose of illustrating the circuits employed in connection with this machine, and in which 1 indicates the line wires and 2 an ordinary switch. 3 indicates the circuit wires of the main circuit in which the motor is located and 4 indicates the circuit wires of the secondary circuit in 45 which the magnet M is located and this secondary circuit it will be noted is connected with and forms a part of the main circuit and is provided with a push button 5. Now, in operation the switch 2, is closed and the 50 contact plates K³ resting upon the insulated portion K' and the button 5 open, the current, of course cannot pass and the machine remains stationary but the moment the button 5 is closed, the current will pass through 55 the magnet M and through the magnet E² setting the motor in operation and this will serve to start the feeding mechanism and the moment the check reaches the finger I, it will trip said finger turning the insulated portion K' away and closing the circuit at 60 that point and all of the operations of the machine will then proceed with the button 5 open.

As before stated, the check after passing 65 from the hopper strikes the finger I bring-

ing the stamping roll around into contact with the platen and the stamping cylinder and operation is completed while the check is being fed between the stamping roll and platen and after the check has been dropped upon the hooked ends L² of the depending arms L' the circuit has been broken and the machine temporarily stopped for the purpose of displaying the check, and after the operator has secured all the information desired from the face of the check and transcribed the same, by means of the adding machine, the button 5 is pressed, withdrawing the arms, dropping the check and starting the machine in operation for feeding the 80 next check.

It will thus be seen that I provide a simple and efficient machine by means of which a series of checks can be successively fed, stamped or indorsed and displayed thereby 85 materially aiding the operator of the adding machine as the said operator has the free use of both hands for the purpose of manipulating the adding machine in the usual manner.

Having thus fully described my invention, what I claim as new and desire to secure by Letters Patent is:—

1. In a machine of the kind described, the combination with means for successively 95 feeding a number of checks, of means for stamping or indorsing said checks so fed, means for arresting the motion of each check and also the operation of the machine, together with means under control of the 100 operator for releasing said check and starting machine.

2. In a machine of the kind described, the combination of means for successively feeding and stamping a series of checks, and arresting each check after stamping and simultaneously stopping the movement of the machine, together with means under control of operator for releasing check and starting machine.

3. In a machine of the kind described, the combination of means for feeding and stamping one check at a time and means for arresting the operation of the machine and holding a check so stamped together with 115 means under control of operator for releasing said check, so held and starting the operation of the machine.

4. In a machine of the kind described, the combination with a hopper terminating in a 120 passage-way, segregating disks arranged in the throat of the hopper, feed rolls arranged opposite and contiguous the segregating disks, a stamping roll and platen arranged upon opposite sides of the passage and projecting into said passage the stamping roll carrying means for making and breaking an electric circuit and means arranged in said circuit for operating the feed rolls and platen, as set forth.

5. In a machine of the kind described, the combination with a hopper terminating in a passage-way, of the follower movable in the hopper, the adjustable segregating disks, 5 arranged in the throat of the hopper, the feed rolls arranged opposite and contiguous the disks, a stamping roll and a platen arranged upon opposite sides of the passage and projecting into said passage, a tripping 10 finger arranged at one end of the stamping roll and projecting into the passage, and a disk arranged at the opposite ends and having an insulated portion for the purpose of breaking the circuit, an electric circuit and 15 means arranged in said circuit for moving the feed rolls, platen and stamping roll, as set forth.

6. In a machine of the kind described, the combination with the feeding mechanism, of 20 the platen and stamping roll, of an insulated disk arranged at one end of the stamping roll, and forming a part of an electric circuit, a finger movable at the opposite end of the stamping roll, said finger projecting 25 horizontally and adapted to be tripped by the fall of a check, for the purpose of closing the circuit and means arranged in, and operated by, said circuit, for the purpose of operating the feeding mechanism, as set 30 forth.

7. In a machine of the kind described, the combination with the hopper, of the segregating disks and feed rolls, the stamping roll and platen, the electric motor and operating devices for moving the feed rolls and 35 platen and a circuit connecting the stamping roll and electric motor, and means carried by the stamping roll for making and breaking said circuit, as specified.

40 8. In a machine of the kind described, the combination with the hopper, of the segregating disks and feed rolls, the stamping roll and platen, the electric motor and operating devices for moving the feed rolls and 45 platen, and a circuit connecting the stamping roll and electric motor and means carried by the stamping roll, for making and breaking said circuit, together with arms for holding the check after it has passed the 50 stamping roll and platen.

9. In a machine of the kind described, the combination with a hopper, disks and feed rolls, of the stamping roll and platen, the hooked arms adapted to catch the check after 55 passing the stamping roll and platen, and

electrically controlled means for releasing said arms, and moving the feed rolls, as set forth.

10. In a machine of the kind described, the combination with the hopper, disks and feed rolls, of the stamping roll and platen, the hooked arms for catching the check after it has passed the stamping roll, electrically controlled means for releasing the arms, and moving the feed rolls, together 60 with means carried by the stamping roll, for making and breaking the circuit controlling the feed-rolls operating mechanism.

11. In a machine of the kind described, a printing or stamping roll arranged opposite a platen and having a flattened face, a finger arranged upon one end of the stamping roll and adapted to have a limited swinging movement between two pins arranged upon the end of the roll, means for 70 normally holding said finger in contact with one of the pins, and a disk arranged at the opposite end of the roll, said disk having an insulating section, for the purpose set forth.

80 12. In a machine of the kind described, the combination with a casing having a hopper at its upper end and a sight-opening in the front face of the case, of the feed rolls and segregating disks arranged in the 85 mouth of the hopper, the stamping roll and platen arranged upon opposite sides of the passage leading from the hopper, a circuit making and breaking device carried by a stamping roll, a tripping finger carried by 90 the stamping roll, and adapted to receive the fall of the check for the purpose of making circuit, depending arms having hooked ends adapted to catch and hold the check opposite the sight openings, an electric motor arranged within the case, and electric circuit connecting said motor, with the stamping roll, electrically controlled means for operating the hooked arms and a circuit closer, controlling the circuit in 95 100 which the electro-magnet controlling the arms is located, said circuit being connected with and secondary to the first mentioned circuit, and means operated by the electric motor for moving the feeding and stamping 105 rolls and platen as set forth.
